UNITED STATES PATENT OFFICE

109,768

DESIGN FOR A RUBBER HEEL

Arthur G. Smith, Elyria, Ohio

Application August 17, 1937, Serial No. 71,149

Term of patent 14 years

To all whom it may concern:

Be it known that I, Arthur G. Smith, a citizen of the United States and resident of Elyria, in the county of Lorain and State of Ohio, have invented a new, original, and ornamental Design for a Rubber Heel, of which the following is a specification, reference being had to the accompanying drawing, forming a part thereof.

I claim:

The ornamental design for a rubber heel, substantially as shown.

ARTHUR G. SMITH.
